(57) **CLAIM**

The ornamental design for a body composition analyzer, as shown and described.

DESCRIPTION

FIG. 1 is a perspective view of a body composition analyzer from the top and front showing our new design;

FIG. 2 is another perspective view from the bottom and rear thereof;

FIG. 3 is a top plan thereof;

FIG. 4 is a bottom plan view thereof;

FIG. 5 is a rear elevation view thereof;

FIG. 6 is a front elevation view thereof;

FIG. 7 is a right side view thereof;

FIG. 8 is a left side view thereof; and,

FIG. 9 is a sectional view thereof taken on line 9-9 of FIG. 4.

The broken line portions in the drawings from no part of the present design.
